UNITED STATES PATENT OFFICE.

HANS BECKERT, OF DRESDEN-LOBTAN, GERMANY.

SWIMMING APPLIANCE.

Application filed December 17, 1927, Serial No. 240,883, and in Germany August 16, 1926.

The present invention has for its object to provide a swimming-appliance consisting of a swimming-shoe arranged with spoon-shaped fins hinged to a sleeve surrounding 5 the ankle-joint.

With known forms of construction the fins are frequently arranged on the movable foot, that is, below the ankle-joint, so that during the swimming-stroke, the fins always remain 10 in a position perpendicular to the middle line of the leg and will only increase the drive in the forward direction.

Now for the purpose of not only increasing the drive in a forward direction but also 15 for giving a buoyancy to the user (especially in the case of non-swimmers) and avoiding a sinking of his legs, the fins together with their sleeve surrounding the angle-joint are kept on the leg and above said ankle-joint in 20 a fixed angular position with respect to the middle line of the leg and slanting toward the heel. Owing to said invariable angle-position the swimmer gets, besides an intense drive in a forward direction, also a 25 buoyancy by which a better swimming-effect and increased power of the swimming-action is secured. For the purpose of still more increasing said swimming-effect the fins arranged in the shape of one-sided spoons have 30 a varying cross-sectional depth, in other words the hollowing is greatest on the side toward the heel.

By these means the advantage is obtained that a greater quantity of water is taken up 35 by the spoon-shaped heel side of the fin and expelled whilst flowing along the nearly straight-portion toward the toe, being thus directed in a downward direction.

A practical embodiment of the present invention is represented in the accompanying 40 drawings, in which,

Fig. 1 represents in a longitudinal elevation the arrangement of the swimming-shoe resting on the foot,

Fig. 2 in a longitudinal back-elevation the swimming-shoe with its fins turned up and

Fig. 3 in a top-view the swimming-shoe.

Fig. 4 shows a view of the ankle-joint sleeve resting on the foot and

Fig. 5 said sleeve in plan.

As seen in the drawing, the swimming-shoe consists of the spoon-shaped fins *a* provided with the stiffening strips or ribs *b*. The fins *a* consist of a resistant material, as 55 for instance aluminium, sheets of duralu-

min or the like and the stiffening strips or ribs *b* for instance of chromed sheets of brass or steel. The fins *a* are hinged to the front part *e* of a sleeve surrounding the ankle-joint and provided also with a yielding 60 rear part *h*. Two resilient elements *f* are arranged adjacent the stiffening ribs *b* so as to contact with the face *g* of the sleeve surrounding the ankle-joint, Fig. 2, for reducing the shock of the fins against the sleeve 65 mentioned.

The sleeve surrounding the ankle-joint is connected with a pin *d* arranged below the sole of the foot by the wire stays *i*, *k*, said pin being covered or surrounded by sponge 70 rubber or the like in order to protect the sole of the foot. Springs *c* can be inserted between the pin *d* and the fins *a* movably fastened to the sleeve surrounding the ankle-joint; by said springs the fins are held or 75 drawn in a downward direction in such a manner that the fins situated at the inner side of the foot neither knock against each other during walking nor touch the floor. In this manner the fins do not hinder the swimmer 80 in any way.

The fins arranged in the shape of one-sided spoons have a varying cross-sectional depth (Fig. 1), in that the greatest depth is found on the side toward the heel for the 85 purpose of taking up on this side the greater quantity of water which flows along the nearly straight portion of the fin and, during the swimming operation, is obliquely directed downwardly. The fins *a* may be provided 90 at their bent stiffening edges with a rubber rim *n* for the purpose of avoiding the user hurting himself by the fin-edges. The sleeve surrounding the ankle-joint can be covered by a layer of sponge rubber or the like *m* to 95 ensure a safe rest of the sleeve around the ankle-joint and prevent said ankle-joint being injured.

The ankle-joint sleeve consists of the front part *e* and the rear yielding part *h* which is 100 fastened to the wire-stays *h* so as to be tilted. On applying the sleeve around the ankle-joint the yielding ends of both halves of the sleeve snap into each other and cause their mutual connection. A plurality of slots *o* 105 are arranged near the yielding ends of the sleeve-half *e*, so allowing the use of the sleeve for different diameters of the ankle-joint. Said part *e* is provided at its longitudinal edge with grooves formed by the flaps *w*, 110

into which the yielding ends of the rear part *h* are introduced, whereby the flat springs *z* carrying noses snap into the slots *o*. The closed sleeve can easily be opened by drawing the flat springs *z* carrying the noses out of the slots *o*.

By the swimming-shoe described above the advantage is obtained that the fins together with their sleeve surrounding the ankle joint are kept on the leg above said ankle joint in a fixed angular position with respect to the middle line of the leg and slanting toward the heel in such a manner that owing to said invariable angle position the swimmer gets, besides an intense drive in a forward direction, also a buoyancy.

What I claim is:

1. A swimming device of the character described comprising, an anklet to be fastened on a limb of a swimmer and spoon shaped propelling members pivotally attached to the anklet, said anklet and members being fastened to the limb above the ankle joint, said members being supported in a fixed angular position with respect to the middle line of the limb and being slanted downward with respect to said line toward the rear of

the ankle to insure an upward as well as forward propelling effect.

2. A swimming device of the character described comprising, an anklet to be fastened on a limb of a swimmer, and propelling members attached to the said anklet, said propelling members being shaped like one-sided spoons and having a greater cross-sectional depth in the portion at the heel.

3. A swimming device of the character described comprising, an anklet to be fastened to a limb of a swimmer, said anklet including a resiliently padded rigid front portion, a resiliently padded rear portion, means for securing said portions together in various adjusted positions, propelling members attached to the front portion, a sole engaging member, and hinged wire stays attached to said front and rear portions and adapted to retain them in proper position and to support the rear portion for pivotal movement with the sole member as a fulcrum to facilitate applying and removing the device.

In testimony, that I claim the foregoing as my invention, I have signed my name this 3rd day of December, 1927.

HANS BECKERT.
